CLAIM

The ornamental design for an earpiece for earphone as shown and described.

DESCRIPTION

FIG. 1 is a perspective view of an earpiece for earphone; FIG. 2 is a front elevational view of the earpiece for earphone, a rear elevational view being identical to the front elevational view;

FIG. 3 is a top plan view of the earpiece for earphone; FIG. 4 is a bottom plan view of the earpiece for earphone; FIG. 5 is a right side elevational view of the earpiece for earphone, a left side elevational view being identical to the right side elevational view; and,

FIG. 6 is a cross-sectional view of the earpiece for earphone taken in the direction of line 6-6 of FIG. 3.

The evenly-dashed broken lines shown in the drawings depict portions of the earpiece for earphone that form no part of the claimed design. The dash-dot broken lines shown in the drawings depict the boundaries of the claimed design and form no part of the claimed design.

1 Claim, 6 Drawing Sheets
